ANTENNA SYSTEM FOR RADIO DRIFT INDICATION

Philip S. Carter, Rocky Point, N. Y., assignor to
Radio Corporation of America, a corporation
of Delaware

Application May 26, 1943, Serial No. 488,584.

14 Claims. (Cl. 250—11.6)

1

The present invention relates to short wave antennas and, more particularly, to antenna systems adapted for use with a radio drift indicator for airplanes.

An object of the present invention is the provision of an antenna system for radio drift measurement and indication.

Another object of the present invention is the provision of a directive antenna system adapted to be mounted on the sides of an airplane fuselage.

Still another object of the present invention is the provision of a highly directive antenna system.

A further object of the present invention is the provision of a directive antenna system adapted to be mounted on a conductive sheet and having its maximum effectiveness at an acute angle to the plane of said sheet.

Still a further object is the provision of a directive antenna system for use with seaplanes which does not disturb the aerodynamics of the plane and which is not liable to water damage in taking off from or alighting upon the surface of the sea.

In determining the drift of the airplane, that is, its motion at right angles to the indicated compass course of radio means, it is proposed to transmit high frequency energy in a pair of sharply directive beams to port and starboard of the plane and directed downwardly at an angle of 45 degrees from the horizontal. The beams, striking a somewhat diffusely reflecting surface, such as the surface of the earth, or the sea below the plane, are reflected and the energy may be picked up by receiving equipment on the plane. If the plane is not drifting the frequencies picked up from each radiated beam are equal and their mixture produces a zero beat indication. If the plane is drifting, due to a Doppler effect, the received frequency from one beam is increased and that from the other is decreased. Their mixture produces a beat, the frequency of which is proportional to the drift speed with relation to the surface below.

The antenna system of the present invention for producing the sharply directive beams normal to the direction of travel of the plane and directed downwardly at angles of 45 degrees, includes a wedge radiator system on each fuselage side wall. The antennae of each wedge system include conductive flaps fastened to the conductive side wall of the plane along their upper edge and forming a small angle therewith so that an open slot is formed along the bottom. A plurality of antennae in horizontal alignment along

2

the side wall may be used so as to increase the fore and aft directivity of the beams. Parasitic reflector wedges may also be provided to concentrate the radiating energy in a single downwardly directed beam. Each wedge antenna may be energized by connecting the central conductor of a concentric transmission line to the inner side of the flap at its longitudinal midpoint while the outer casing of the transmission line is connected to the wall of the plane. The individual transmission lines for each antenna of equal length, so that the antennae are energized in phase, may be connected in parallel in a conventional manner.

15 The present invention will be more fully understood by reference to the following detailed description, which is accompanied by a drawing wherein Figures 1 and 2 illustrate the relationship of the desired radiation patterns of the antenna of the present invention with respect to a plane on which the antennas may be mounted, while Figure 3 illustrates an end view of an embodiment of the present invention, while Figure 4 is a side view of the embodiment and Figure 5 is a directivity pattern of the antenna; Figure 6 illustrates a modification of the present invention and Figure 7 is a vertical directivity pattern of the modification of Figure 6, while Figure 8 illustrates a further modification of the present invention, Figure 9 is a horizontal directivity pattern of the modification of Figure 8; Figures 10 and 11 are side and end views of a portion of a further modification of the present invention, Figure 12 is a diagram of a transmission line assembled for use with the antenna of Figures 10 and 11, while Figures 13 and 14 illustrate the radio frequency field distribution in a wedge resonant chamber and Figure 15 is a curve useful in determining the proper dimensions of the antenna elements.

40 In Figures 1 and 2 are shown plan and elevation views of an airplane 1 having mounted on the port and starboard sides of the hull, antenna systems 2 and 3. As before pointed out, it is desired to transmit high frequency energy in a pair of sharply directive beams such as the beams 2b and 3b to port and starboard of the plane 1 and directed downwardly at an angle of 45 degrees, as shown in Figure 2 in the elevational view. The beams of energy striking a somewhat diffusely reflecting surface such as the surface of sea S below the plane are reflected and the energy may be picked up by the antennae 2 and 3 and applied to suitable receiving equipment on the plane. If plane 1 is not drifting the frequencies

picked up from each radiated beam pb and sb are equal and their mixture in the receiving equipment produces a zero beat indication. If the plane is drifting to port, for example, the energy transmitted from antenna 2 is reflected from surface of S and again received by antenna 2. Due to the antenna traveling in the opposite direction to the returning waves a Doppler effect causes the frequency of the returning energy to be higher than when radiated. The opposite effect takes place on the energy radiated and received from antenna 3. The mixture of the two received energies of different frequencies produces a beat note the frequency of which is proportional to the drift speed with relation to the surface S.

In Figures 3 and 4, reference numeral 10 indicates, generally, a vertical conductive sheet which may be considered to be a side wall of the fuselage of a plane. The dimensions of sheet 10 preferably are at least .3 wavelengths in height by 4 wavelengths long in order to obtain the desired directivity patterns. An elongated conductive flap 12 is fastened along its upper edge to the conductive sheet 10 and is bent outwardly to form a small angle with respect to the outer face of sheet 10. The ends are preferably closed, as shown by end walls 12' but may be open if desired. The length of flap 12 is preferably of the order of one wave length. When the ends are closed the width depends upon the length. The relationship between the length of flap 12 and its width will be made more clear with reference to the curve of Figure 15 which will be described later. At approximately the longitudinal midpoint of flap 12 is connected the central conductor 14 of a concentric transmission line 15, while the outer casing 16 thereof is connected to the conductive sheet 10. The vertical distance between the lower edge of flap 12 and the point of connection of conductor 14 may be so chosen as to obtain an impedance of a particular value at the termination of line 15.

In Figure 5 curve 20 indicates the directivity pattern of the antenna of Figures 3 and 4 in terms of power versus angles from a line normal to the intersection of sheet 10 with a reference plane indicated by line 5, 5 of Figure 4.

It will be readily apparent, from an inspection of Figure 5, that even though only a single radiator element is used in the modification of Figures 3 and 4 there is obtained a directivity pattern which is sharply directive in the plane identified by line 5, 5. It will be noted that in this plane there is an entire absence of secondary lobes or ears. However, the pattern in the vertical plane contains, in addition to a downwardly directed main beam, an upwardly directed lobe of considerable amplitude. It is desirable that all, or substantially all, of the radiated energy be directed downwardly where it may be usefully employed and for this reason supplemental parasitic radiating elements may be added to the antenna of Figure 4. This modification is shown in Figure 6 wherein, in addition to the flap 12 and the associated transmission line, a parasitic reflector flap 22 is used. The reflector flap is disposed in a plane parallel to the plane of flap 12 and spaced therefrom a short distance. The lower free edges of flaps 12 and 22 are, in this modification, provided with adjustable edge pieces 13 and 23 for fine adjustment of the tuning of the flaps. Their position may be adjusted during tests and then soldered or clamped in position by suitable fixing means. Due to the presence of the reflector flap

22 the directivity pattern of the antenna in the vertical plane is improved in that radiation in upward directions is reduced. The pattern is shown in Figure 7, curve 25. It will be noted that the maximum of the curve occurs at an angle of about 40 degrees below the horizontal in substantially a single beam. The energy which, in the previously described embodiment was wasted in the upwardly directed lobe, is now combined with the energy radiated in the desired direction and contributes to the desired useful result. The incidental small ears appearing above the horizontal axis of the curve are not seriously objectionable since they are not only very small but are at such an angle that in most cases they will not reach the surface below the plane from which the energy is to be reflected unless, of course, the antenna system is placed directly beneath the wings of the plane. It is generally not necessary that the antenna system be so placed.

The modification of the present invention shown in Figure 8 utilizes a longitudinal array of four of the wedge antennas and parasitic reflectors which were shown in vertical section in Figure 6. The elements are arranged in horizontal alignment, in two pairs, in order to increase the fore and aft directivity of the radiated beam. In the particular modification shown in Figure 8, it will be noted that the spacing between the individual wedge antennas is not uniform, the spacing between the center pair being greater than that between adjacent pairs. This variation in spacing was necessary because of the particular construction of a plane with which this antenna system was designed to be used. If possible to do so, it is, of course, preferable to arrange all of the antennas and their associated reflectors as close together in the horizontal plane as possible. The directivity pattern of the antenna of Figure 8 is shown in Figure 9, curve 35 indicating the theoretical directivity pattern, while 36 indicates the actual measured directivity pattern. The presence of the small side ears in the directivity pattern of Figure 9 are due to the increased spacing between the two middle radiators and may be eliminated when all radiators are spaced as closely together as possible.

It will be noted that the measured and theoretical patterns agree quite closely, one with the other, both being characterized by the absence of large supplemental or side ears and an extremely sharp main lobe.

A further modification of the present invention is shown in the side view of Figure 10 and end view of Figure 11. This modification utilizes a different means for tuning the parasitic reflector flap 42 than that shown in Figure 6. Here a capacity plate 43 is mounted on a threaded stud T screwed through a bushing at the outer edge of flap 42 between the flap and the portion of flap 52 which is overlapped by flap 42. By adjusting the spacing of plate 43 with respect to flap 52 the capacity may be adjusted so as to tune the parasitic radiator to resonance. The energized antenna 52 is connected to a transmission line TL having an inner conductor 51 and an outer shell 50. This antenna is tuned as shown in Figure 12 by means of a tuning stub 60 connected across transmission line TL. The inner conductor 61 of stub 60 is arranged to be shorted to the outer wall by a slidably bridge 62. By properly sliding slider 62 the reactance of the stub may be either capacitive or inductive as desired, thus in effect tuning the wedge antenna 52. The transmission line feed system for the antenna

5

52 of Figures 10 and 11 in addition to tuning stub 60, has connected thereacross an impedance matching stub 70 having an inner conductor 71 and an adjustable shorting slider 72 for adjusting the impedance of the transmission line to a value equal to that of the antenna to which it is connected. The antenna elements are coupled together in pairs and connected in a parallel relationship to transmission line TL'. At substantially the midpoint of transmission line TL' is placed a slidable T piece 80 having within the leg of the T an inner conductor 81 adapted to contact the inner conductor 51' of transmission line TL'. The leg of the T piece 80 and the inner conductor 81 therewithin are connected to a final transmission line TL'' which is connected to the transducer equipment. The purpose of having the slidable T piece 80 at the midpoint of transmission line TL' is to permit final adjustment of the balance of the antenna on each side of the plane after installation.

Due to the presence of the wings of the plane and other causes, it may be found that the radiated beams *pb* or *sb* of Figures 1 and 2 are not truly vertical to the line of travel of the plane. By shifting T piece 80 along the length of transmission line TL' the horizontal angles of the corresponding beam may be slightly shifted to assume perpendicularity. It should be noted that only slightly over half of the transmission line system for energizing the antennas on one side of the plane is shown. The portion not shown is exactly similar to that shown, the layout being substantially symmetrical about the midpoint of transmission line TL'.

Since the antenna shown in Figures 10 and 11 is mounted on the exterior of the plane where it is exposed to weather conditions and, more particularly, to a great deal of spray when the plane is leaning on or taking off from the surface of the sea it is desirable that the open edge of the wedges be closed to prevent the entrance of moisture. This may be done by means of closing walls 44 of high quality dielectric material such as methyl methacrylate. As in the previously described embodiments, the ends of the wedge antenna and reflector are closed by walls 40 which also act as supporting means to maintaining the angular relationship of the flaps with respect to the side wall 10.

The theory of operation of the wedge antenna may be more easily understood if the theory of operation of cavity resonators energized in the lowest order transverse electric mode is considered. A cylindrical cavity resonator energized in this mode has its electric field transverse to the axis of the cavity, the lines of force forming concentric circles, and the magnetic field parallel to the axis in the form of closed loops in radial planes. Theoretically, a small section of the cavity may be considered by itself if the section considered is bounded by conductive walls normal to the electric field lines, said walls forming a completing path for the lines. Likewise, the outer edge of the section should be completed by a boundary such that no magnetic field may escape, a sort of fictitious magnetic short circuit. The small sector will then operate exactly the same as though it still formed a part of the whole cavity.

This situation is shown in Figure 13, wherein is represented a wedge shaped sector of the field within a cylindrical cavity resonator, the arrows H representing the magnetic field and terminate along boundary surface MS indicating a mag-

6

netic short-circuit. There is, of course, no actual magnetic short-circuit but the magnetic lines of force H having boundary MS at the bottom of the figure progress across to the inner side of the wedge upwardly along the length of the wedge and back to the right and again terminate along boundary MS. Curve *Ha* along the left-hand side of the figure indicates the distribution of the magnetic field in a graphical form. The electric field indicated by arrows E and curve *Eh* is, of course, a maximum at the midpoint of the wedge and must be zero at each end due to the end walls being closed.

10 The distribution of the magnetic and electric fields as though viewed from the end of the wedge of Figure 13 are shown in Figure 14. It will be seen from curve *Ha* that the magnetic field decreases from a maximum at the apex of the wedge to a minimum at the outer part of the wedge. It will be noted from curve E of Figure 14 that the electric field increases smoothly from a zero value at the apex of the wedge to a maximum at the open side of the wedge. The relationship

$$25 \frac{h}{\lambda}$$

of the length of the wedge resonator to the wavelength and the relationship

$$30 \frac{a}{\lambda}$$

of the width of the wedge resonator to the wavelength are interdependent and with either given the other may be determined by curve 90 of Figure 15. Within certain limits either the distance *a* or *h* may be arbitrarily chosen and the other dimension obtained from the curve. It will be noted that the curve is asymptotic to a value of

$$40 \frac{h}{\lambda}$$

of .5 and a value of

$$45 \frac{a}{\lambda}$$

of .383 so it will ordinarily be more desirable to choose values so that the midportion of curve 90 is used.

50 In the foregoing description and in the accompanying drawing, some specific dimensions which have been found in practice to work well have been indicated. However, it should be distinctly understood that my invention is not to be limited to these particular dimensions, nor to the particular embodiments described, but that modifications within the scope of the invention may be made.

I claim:

1. A directive antenna including a conductive base sheet having a radiator element associated therewith in the form of a long narrow conductive flap attached along one edge to said base sheet and forming a small angle with respect to the plane of said sheet and a two conductor transmission line having one conductor connected to said sheet and the other to said flap at a point intermediate its ends.
2. A directive antenna including a conductive base sheet having a radiator element associated therewith in the form of a long narrow conductive flap attached along one edge to said base sheet and forming a small angle with respect to the plane of said sheet and a two conductor transmission line having one conductor connected to said sheet and the other to said flap at a point intermediate its ends.
3. A directive antenna including a conductive base sheet having a radiator element associated therewith in the form of a long narrow conductive flap attached along one edge to said base sheet and forming a small angle with respect to the plane of said sheet and a two conductor transmission line having one conductor connected to said sheet and the other to said flap at a point intermediate its ends.

point intermediate its ends, said sheet having dimensions of the order of several times the operating wavelength of said system.

3. A directive system including a conductive base sheet having a radiator element associated therewith in the form of an elongated conductive flap attached along one edge to said base sheet and forming a small angle with respect to the plane of said sheet and means for coupling high frequency transducer means to substantially the longitudinal midpoint of said flap and to said sheet, said sheet having dimensions of the order of several times the operating wavelength of said system, said flap having a length of the order of the operating wavelength, and a width of the order of .3 to .5 of the operating wavelength.

4. A directive antenna including a conductive base sheet having a radiator element associated therewith in the form of an elongated conductive flap attached along one edge to said base sheet and forming a small angle with respect to the plane of said sheet, and a parasitic reflector element including a second flap attached to said sheet along one edge and lying in a plane parallel to the plane of said first flap and closely adjacent thereto.

5. A directive antenna including a conductive base sheet having a radiator element associated therewith in the form of an elongated conductive flap attached along one edge to said base sheet and forming a small angle with respect to the plane of said sheet, and a parasitic reflector element including a second flap attached to said sheet along one edge and lying in a plane parallel to the plane of said first flap and closely adjacent thereto, and means for tuning each of said elements including an adjustable edge piece associated with the free edges thereof.

6. A directive antenna including a conductive base sheet having a radiator element associated therewith in the form of an elongated conductive flap attached along one edge to said base sheet and forming a small angle with respect to the plane of said sheet, and a parasitic reflector element including a second flap attached to said sheet along one edge and lying in a plane parallel to the plane of said first flap and closely adjacent thereto, and an adjustable capacity plate connected to the free edge of at least one of said elements for tuning said element.

7. A directive antenna including a conductive base sheet having a radiator element associated therewith in the form of an elongated conductive flap attached along one edge to said base sheet and forming a small angle with respect to the plane of said sheet, and a parasitic reflector element including a second flap attached to said sheet along one edge and lying in a plane parallel to the plane of said first flap and closely adjacent thereto and a transmission line coupled to said radiator element, said transmission line having a shunt branch connected thereto for tuning said radiator element, and means for tuning each of said elements including an adjustable edge piece associated with the free edges thereof.

8. A directive antenna array including a plurality of systems, as set forth in claim 4, arranged in end to end alignment, all the said systems being energized in an in phase relationship.

9. An antenna system for drift indication including an antenna as set forth in claim 4, so mounted on a side wall of the fuselage of an airplane that a sharply directive beam of high frequency energy is directed downwardly at an angle of substantially 45 degrees in a plane normal to the direction of flight of said airplane.

10. An antenna system for drift indication including a pair of antennae as set forth in claim 1, so mounted over each side wall of the fuselage of an airplane that a pair of sharply directive beams of high frequency energy are directed downwardly at an angle of substantially 45 degrees in a plane normal to the direction of flight of said airplane.

11. An antenna system for drift indication including a pair of antennae as set forth in claim 4, so mounted over each side wall of the fuselage of an airplane that a pair of sharply directive beams of high frequency energy are directed downwardly at an angle of substantially 45 degrees in a plane normal to the direction of flight of said airplane.

12. A directive antenna including a conductive base sheet having a radiator element associated therewith in the form of an elongated substantially rectangular conductive flap attached along one edge thereof to said base sheet within the area of said sheet, and forming a small angle with respect to the plane of said sheet and means for coupling high frequency transducer means between said flap and said sheet at a point near the longitudinal midpoint of said flap.

13. A directive antenna including a conductive base sheet having a plurality of radiator elements associated therewith, each of said radiator elements being in the form of a long narrow conductive flap attached along one edge of said base sheet within its area and forming a small angle with respect to the plane of said sheet, said radiator elements being arranged in end-to-end alignment, all of the said elements being energized in an in phase relationship.

14. An antenna system for drift indication including a long narrow conductive flap attached along one edge to a conductive side wall of the fuselage of an airplane and forming a small angle with respect to the plane of said side wall, said flap being so arranged that a sharply directive beam of high frequency energy is directed downwardly at an angle of substantially 45° in a plane normal to the direction of flight of said airplane.
